UNITED STATES PATENT OFFICE.

GEORGE H. FRASER, OF BROOKLYN, NEW YORK.

MACHINE FOR CRUSHING AND GRINDING.

Application filed March 31, 1917, Serial No. 158,825. Renewed December 15, 1922.

To all whom it may concern:

Be it known that I, GEORGE H. FRASER, a citizen of the United States, residing in the borough of Brooklyn, county of Kings, city and State of New York, have invented certain new and useful Improvements in Machines for Crushing and Grinding, being a refiling of my application Ser. No. 803,494, filed Nov. 28, 1913, of which the following is a specification.

This invention relates to machines for crushing, grinding or pulverizing materials, and aims to provide certain improvements therein.

The invention relates more particularly to rock crushers of the type having a plurality of crushing rolls within an annular die in which the crushing is effected between the periphery of the rolls and the inner face 20 of the die. In some examples of such machines the die revolves and is either held in position yieldingly by the rolls which support it, or rigidly by a shaft supported in fixed bearings and connected to the die 25 by a head or spider, the rolls being pressed outwardly by springs to resist a crushing pressure from the inner face of the die, and being movable radially of the latter to yield to adapt themselves to the work. Means 30 are generally provided for driving one of these parts, and the other parts are generally rotated by traction from the driven part.

My present invention aims to provide an improved crusher or pulverizer especially applicable to the type in which the die is mounted on a fixed axis and is the driven member, but includes many features of improvement which can be employed in other 40 types of crushers.

To this end in carrying out my present invention in its preferred form, I provide an improved arrangement of the die and rolls, improved means for carrying the 45 rolls, improved means for guiding them, means for transmitting all or part of the crushing thrust from one roll to another, improved means for holding the die, improved means for controlling the size of 50 material discharged from the die, and various details of improvement in the construction and the arrangement of the several parts of the machine, all of which will

be more fully hereinafter set forth with reference to the accompanying drawings, in which,—

Fig. 1 is a side elevation partly in vertical axial mid-section, of a crusher in which the die is driven and mounted on a fixed axis, showing the preferred form of 60 my invention as adapted to a crusher of this type;

Fig. 2 is a front elevation thereof partly broken away and in section on the lines 2—2 of Fig. 1 to show the internal parts; 65 and

Fig. 3 is a fragmentary rear elevation thereof partly broken away and in section on the lines 3—3 of Fig. 1 to show the internal parts.

Referring to the drawings, let A indicate a frame, B the ring or die, C the rolls, D their shafts or axles, E the roll carriers or bearings, S the crushing springs or means, and d the adjusting screw.

In the type of machine shown, the ring revolves at a speed sufficient to cause the material to be crushed to be held on the concave inner crushing face of the ring by centrifugal force, and the rolls are rotatably held and are pressed against this face to crush the material thereon. The material as crushed is forced over the edges of the ring and falls through the outlet a in the base. When the ring is the driven member as here shown, it is carried by a hollow wheel or cup-shaped head or spider G mounted on a shaft H carried from supports I on the base A, and is driven in any suitable manner, as by a pulley J which 90 may be mounted on a shaft K¹ with clutch L¹ and pinion M driving gear M¹ on shaft H.

Power applied to revolve the ring causes the rolls to revolve by traction, and the movable roll carriers permit the rolls to move inwardly to adapt themselves to the crushing operation. Material is fed on the inner face of the descending side of the ring in front of one of the lower rolls from a feed hopper N through a chute O, and revolves with the ring, passing under the rolls until crushed sufficiently to flow over the sides of the ring. The ring and rolls are enclosed in a crushing chamber in the casing P.

As thus far described the parts may be

of any usual or suitable construction, and operate according to any known principle for such machines.

According to one feature of my invention I provide an improved construction of ring and head and connection between them, whereby the ring is flexibly carried from the head, and danger of crystallization and breakage of the parts is reduced. The head 10 G is preferably a disc having a tapered hub keyed on the front end of the shaft H, to which disc are fastened a number of separable and slightly flexible or yielding arms or spokes b, extending forwardly and preferably in parallelism with the shaft H, which at their forward ends are separably connected to the ring B, preferably by passing through holes c in a narrow flange or lug e on the outer periphery of the ring, which is clamped against the spokes by nuts f to make a separable but not absolutely rigid connection between the ring and head. The spokes or arms b constitute a cage between the head and ring, through which discharge from the ring can pass to the casing, and by which the ring can be held and driven from the head with an amount of flexibility determined by the size or character of the spokes, and the tightness with which they are attached to the respective parts. Preferably the spokes are slender enough and of sufficiently flexible material, as wrought iron or steel, to give a very slight motion between the head and ring sufficient to prevent the vibration of the latter from crystallizing the cast metal of the head or the drive shaft, but not so much as to prevent the desired holding, driving and positioning of the ring from the head. As shown, the spokes b have reduced rear ends 40 g fitting holes h in the disc and held therein by nuts i, and the body of the spokes is enough larger than its ends to provide shoulders against which the head and ring may be clamped more or less tightly to position them and hold them with the desired tightness to give more or less flexibility.

According to another feature of improvement, each crushing roll is supported at each side of the ring to resist a crushing pressure from the inner face of the latter, and means are preferably provided for equalizing the pressure at each side of the roll, and when two or more rolls are used, these means preferably react from each roll toward the other 55 or others, and from each side of the rolls toward the corresponding means at the other side of the rolls, to the end of utilizing all the pressure and thrusts of the rolls as a crushing force, and apportioning this between the rolls so that it will be uniform or balanced at each side thereof.

Preferably each roll is movably carried so that it can move in parallelism with the axis of the die, as by being pivotally mounted to swing on an axis parallel with that

of the shaft H. As shown, the frame A carries a hollow or tubular or apertured support or member Z which is pivotally or slidably detachably connected to it by pivotal bolts T and extends upwardly at the side of the die, and has three approximately equidistant ears j, one at the bottom and the others near the top of its upwardly extending front, which have bores k in which are mounted or fixed pivotal shafts or pins l extending through the interior of the die and projecting outwardly at the front side of the frame or support Z, and between these ears the frame is formed with curved sides m which surround the upper ears, so that the front of the frame is open and its interior is hollow for giving access to the rolls or permitting their removal.

Each roll carrier E preferably comprises an inner member n having a tubular barrel or sleeve fitting over and pivotally mounted on the pin l, and having an integral arm o having a bored head p in which the axle D is fixed or keyed within the spider. The axle D extends through the roll and projects in front of the ear j and into line with the front end of the pin l, and the front side of the carrier E comprises a separate arm q pivotally mounted on the front end of the pin l and having a bored head r fitting over and fixed or keyed to the front end of the axle.

As shown, the top roll is pivotally mounted from a point slightly below its shaft, the feed roll is suspended from a point above its shaft, and the other roll is supported from a point below its shaft and intermediate of its end and the other lower roll, so that its carrier inclines upwardly and outwardly and each carrier is pivoted in advance of the point at which its roll engages the ring, so that in use the rolls pull on the carriers as tension members as the ring revolves when the feed hopper is on the side shown. This arrangement is not essential, however, as the feed hopper may be placed on the other side, a seat s therefor being provided at each side, so that when desired the feed can be against the carriers, which will then act as compression members in resisting the tendency of the rolls to travel with the ring.

When the rolls are rotatably mounted on the carriers by revolving on fixed axles or studs as shown, the bore of the roll hub is sufficiently large to permit placing a semi-circular lining of bearing metal within it, which is keyed on the pressure side of the axle to protect the latter from wear from the roll. The hub t of each roll is held between the heads p and r of the carriers to position it axially, and the parts are lubricated in any suitable manner, as by an oil duct u extending through the axle and discharging within the hub. Waste oil is removed by escaping through the keyway v,

which it reaches at each end of the hub, and entrance of dust or leakage of oil is prevented by a cup-shaped washer *w* on each end of the hub, which embraces the latter and revolves with it, but is pressed against the carrier by springs *x* to allow slight axial movement of the roll while preserving a right joint around the shaft.

Each roll is held or pressed outwardly uniformly at each side of its crushing face, by compression means at each side of the roll preferably reacting against or supported by similar means at the other side of the roll, and acting expansively to permit desired radial movements of the roll and axially to balance the load at each side of the roll, and these means preferably react toward two or more of the rolls with a force that is countervailing in two or more directions, so that the pressure and thrusts incident to crushing are confined within the ring and utilized between the several rolls as crushing forces. This may be accomplished in various ways, but I prefer to use the means shown, in which a radially and axially movable thrust member or link *K* is pivotally connected to each carrier head and inclines inwardly and is pivotally connected to a sliding, floating, or axially movable or adjustable member or transmitter *L*, which receives the thrust of each member *K* and transmits it to each other member, and moves both axially and radially to equalize the thrusts between the members *K* at one side of the roll, and to adapt itself to their variations in inclination incident to movements of the respective rolls. The thrust members *K* have pivotal connections permitting their movements in the several directions necessary to both axial and radial movement of the transmitter *L*, and the parts are preferably formed with abutting faces *y* or other knuckle joint provisions limiting their relative movement past a predetermined point, as the dead center for example, by which excessive movement is prevented, while the necessary intermediate movements are permitted. The compression members and transmitters are preferably duplicated at each side of the roll, and the transmitters are disposed inwardly of the carriers, so that the compression members diverge or incline outwardly, radially and axially, and expand as the transmitters are moved apart, and collapse as they are moved toward each other, and between the transmitters are disposed preferably right hand and left hand adjusting screws acting expansively, axially of the die, to force the transmitters outwardly and cause the compression members to act obliquely to hold the carriers and their rolls outwardly to resist a crushing pressure. The transmitters shown are slidingly feathered axially, and have respectively right hand and left hand screwthreads engaging the screw *d* by which

the transmitters can be adjusted toward or from one another to compress the springs against the transmitters and increase or diminish their action, either to increase crushing pressure or take up wear. By screwing the transmitters together sufficiently the parts can be collapsed to permit the rolls to move inwardly to clear the concavity of the ring for permitting removal of any roll, or of all the rolls from the ring. Each transmitter is prevented from rotation by a forked arm *a'* engaging some fixed part, as the hub *n* for example, which serves to prevent displacement while permitting necessary movement. The inward collapsing of the thrust members gives ample room for adjustment opposite the hub of the spider, and the knuckle joint preventing adjustment past the dead center ensures against the thrust members getting into contact with the end of the shaft *H*.

My invention preferably provides means for supporting the pivotal studs internally of the spider, which is preferably done by connections or tie bars *b'* extending from one stud to another and pinned on the ends of these inwardly of the carriers, so that a strain applied to either stud is transmitted to the others, and all are bound together at their inner ends.

To control the size of material escaping from the die, my invention provides a cheek piece preferably at each side of the die, which is fixed, preferably adjustably, at a point distant from the side face of the die corresponding to the maximum size desired for the crushed product, and held in this position by supports extending through the interior of the die. Preferably an annular cheek piece *Q* is mounted at each side of the die adjustably on three or more fixed rods *R* which are removably carried in holes *c'* in the support *Z*, and serve to hold the cheek pieces rigidly in the desired position relatively to the rigidly held die so that a uniform space for discharge of material is maintained at each side of the latter.

The casing *P* is shown as a sheet metal casing removably mounted on the frame *A* and enclosing the crushing parts and support *Z*.

In operation, when the ring is supported as shown, it will support the rolls, which will be movable as a group passively to adapt themselves to the ring or the material therein, and individually movable radially to exert a crushing pressure, and to equalize the crushing pressure of each. The means pressing each roll outwardly will react against the others, and the expansive means at each side of the rolls will ensure a crushing pressure directly in the line of work. The balancing means extending through the ring from one side to the other of the roll comprising the screw *d* in the construction

shown will balance the load and relieve the parts of any uneven strains, apportioning the load uniformly over the bearing surfaces and pivotal provisions.

5 The transmitters will float radially to equalize the thrust members at the respective sides of the rolls, and the adjusting screw and pressure springs will float axially to balance the load between the two sides of 10 the rolls. The screw will act as an axial compression member, and also serve for adjustment to vary pressure or take up wear, and for collapsing the parts to permit removals.

15 The support Z and the entire internal mechanism can be bodily withdrawn from the ring upon disconnecting the internal cheek piece, whereupon these parts can be withdrawn forwardly by sliding the support outwardly on the base, or they can be swung out of the die by swinging the support on either of its attaching bolts as a pivot. The ring can then be disconnected from the spider and another placed thereon.

20 25 If preferred the support Z and the internal parts may remain stationary, and the ring and spider may be removed by sliding these and their supports I rearwardly upon releasing them from the base.

30 35 It will be understood that my invention is not limited to the particular details of construction, arrangement and combination of parts, set forth and shown as constituting its preferred form, nor to the particular 40 type of machine to which it is shown as applied, since my improvements can be availed of in whole or in part in connection with such types of machines or according to such modifications or adaptations, as circumstances or the judgment of those skilled in the art may dictate, without departing from the spirit of the invention.

45 The support Z has a bifurcated portion comprising rearward feet U straddling the ring as shown in Fig. 3 and projecting rearwardly beyond the center of gravity of the weight it carries and traversed by its pivotal bolts T, and the support I has a bifurcated portion comprising forwardly projecting feet V meeting the feet U and forming with them the upper part of the outlet a as best seen in Fig. 1.

50 55 I do not claim herein the improvements claimed in my companion applications Number 158,824 filed March 31, 1917, and Number 158,823 filed March 31, 1917.

What I claim is:—

1. In combination, an annular crushing die revolving in an approximately vertical plane on a fixed axis and having an internal crushing face, a movable and rotatable crushing roll within and eccentric of said die and having a peripheral crushing face reciprocal to the inner face of said die, 60 means for revolving one of said parts, a

revolving head at one side and rotatably sustaining said die, movable non-rotative means on which said roll is rotatably mounted in parallelism with and movable at right angles to the axis of said die, a one sided support for said roll mounted exteriorly of said die and having a portion extending past one side of said die movably sustaining said non-rotative means solely from such side of said die, and a pivotal connection between said non-rotative means and said supporting means axially parallel with the axis of said die. 75

2. In combination, an annular crushing die having an internal crushing face, a movable and rotatable crushing roll within and eccentric to said die and having a crushing face reciprocal to that of the latter, means for revolving one of said parts, a frame for supporting said parts comprising a support 80 member at the side of said die, and a movable carrier on which said roll is rotatably mounted comprising an arm at the inner side of said roll having a rigid portion extending through said die and movably mounted on said member at the inner side thereof, and a separable portion at the outer side of said member movably mounted thereon and separably connected to said inner portion of said carrier. 90

3. In combination, an annular crushing die revolving in an approximately vertical plane and having an internal crushing face, a rotatable crushing roll within and eccentric of said die and having a peripheral crushing face reciprocal to the inner face of said die, means for revolving one of said parts, means affording a base for said parts affording an outlet aperture below said die, and a non-rotative support for said roll mounted exteriorly of and below said die and having a portion extending past one side of said die on which said roll is rotatably sustained and having a laterally projecting bifurcated portion below and extending beneath the periphery of said die at each side of said outlet aperture for sustaining said support from said base and affording an opening below said die to said aperture. 100 110 115

4. In combination, an annular crushing die revolving on a fixed axis and having an internal crushing face, a movable and rotatable crushing roll within and eccentric to said die and having a crushing face reciprocal to that of the latter, means for revolving one of said parts, a revolving member connected to one side of said die, a frame for 120 said parts comprising a supporting portion at the other side of said die, non-rotary cheek pieces mounted at the inner and outer sides of said die and between which said die rotates, and a support for the inner one of said cheek pieces extending through said die. 125

5. In combination, an annular crushing 130

- die revolving in an approximately vertical plane and having an internal crushing face, a movable and rotatable crushing roll within and eccentric of said die and having a 5 peripheral crushing face reciprocal to the inner face of said die, means for revolving one of said parts, means for supporting said parts, non-rotative movable means on which said roll is rotatably mounted, and axially 10 obliquely outwardly inclined holding means inwardly of the axis of said roll and opposite and acting radially and obliquely outwardly against said non-rotative means to hold said roll outwardly toward the inner face of 15 said die to resist a crushing pressure therefrom.
6. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, means for supporting said parts, non-rotative movable means on which said roll is rotatably mounted, axially obliquely outwardly inclined holding means inwardly of the axis of said roll and opposite and acting radially and obliquely outwardly against said 25 non-rotative means to hold said roll outwardly toward the inner face of said die to resist a crushing pressure therefrom, and axially movable obliquely adjusting sustaining means movable axially of said die and sustaining said holding means for varying the inclination thereof.
7. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, means for supporting said parts, non-rotative movable means on which said roll is rotatably mounted, axially obliquely outwardly inclined holding means inwardly of the axis of said roll and opposite and acting radially and obliquely outwardly against said 30 non-rotative means to hold said roll outwardly toward the inner face of said die to resist a crushing pressure therefrom, and axially movable sustaining means movable transversely of the direction of stress of said holding means for varying the inclination thereof.
8. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, means for supporting said parts, non-rotative movable means on which said roll is rotatably mounted, axially obliquely outwardly inclined holding means inwardly of the axis of said roll and opposite and acting radially and obliquely outwardly against said 35 non-rotative means to hold said roll outwardly toward the inner face of said die to resist a crushing pressure therefrom, and axially movable sustaining means movable axially of said die and sustaining said holding means for varying the inclination thereof.
9. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, means for supporting said parts, non-rotative movable means on which said roll is rotatably mounted, axially obliquely outwardly inclined holding means inwardly of the axis of said roll and opposite and acting radially and obliquely outwardly against said non-rotative means for pressing said roll outwardly toward the inner face of said die to resist a crushing pressure therefrom, and means for radially adjusting said 40 pressing means.
10. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, means for supporting said parts, non-rotative movable means on which said roll is rotatably mounted, axially obliquely outwardly inclined holding means inwardly of the axis of said roll and opposite and acting radially and obliquely outwardly against said non-rotative means to hold said roll outwardly toward the inner face of said die to resist a crushing pressure therefrom, and axially movable obliquely adjusting sustaining means movable axially of said die and sustaining said holding means for varying the inclination thereof.
11. In combination, an annular crushing die revolving on a fixed axis and having an internal crushing face, three or more rotatable crushing rolls within and eccentric to said die and each having a crushing face reciprocal to that of the latter, means for revolving one of said parts, movable carriers on which said rolls are rotatably mounted respectively, and means obliquely outwardly reversely inclined pressing approximately radially outwardly toward said carriers intermediate thereof and reacting axially against each other to hold said rolls outwardly to resist a crushing pressure from the inner face of said die.
12. In combination, an annular crushing die revolving on a fixed axis and having an internal crushing face, three or more rotatable crushing rolls within and eccentric to said die and each having a crushing face reciprocal to that of the latter, means for revolving one of said parts, movable carriers on which said rolls are rotatably mounted respectively, and means obliquely outwardly reversely inclined pressing approximately radially outwardly toward said carriers intermediate thereof and reacting axially against each other to hold said rolls outwardly to resist a crushing pressure from the inner face of said die.

- tatable crushing rolls within and eccentric to said die and each having a crushing face reciprocal to that of the latter, means for revolving one of said parts, movable means 5 on which said rolls are mounted respectively, and inclined means intermediate of, normally inclined axially inwardly from, and adapted to react obliquely outwardly toward said carriers for holding said rolls outwardly to resist a crushing pressure from the inner face of said die.
13. In combination, an annular crushing die revolving in an approximately vertical plane and having an internal crushing face, 15 a movable and rotatable crushing roll within and eccentric of said die and having a peripheral crushing face reciprocal to the inner face of said die, means for revolving one of said parts, non-rotative movable means on which said roll is rotatably mounted, oppositely obliquely outwardly mutually sustaining inclined holding means inwardly of the axis of said roll and opposite and adapted to react obliquely radially outwardly toward said non-rotative means to hold said roll outwardly toward the inner face of said die to resist a crushing pressure therefrom, and adjusting means for adjusting said holding means from one another.
14. In combination, an annular crushing die revolving on a fixed axis and having an internal crushing face, two or more movable and rotatable crushing rolls within and eccentric to said die and each having a crushing face reciprocal to that of the latter, means for revolving one of said parts, movable carriers on which said rolls are rotatably mounted respectively, expansively acting means intermediate of said carriers, and 30 axially movable means intermediate of said expansively acting means for receiving and
15. In combination, an annular crushing die revolving on a fixed axis and having an internal crushing face, a movable and rotatable crushing roll within and eccentric to said die and having a crushing face reciprocal to that of the latter, means for revolving one of said parts, movable means on which said roll is rotatably mounted, and axially and inwardly collapsible means at each side of said roll inwardly of said movable means for holding said roll outwardly to resist a crushing pressure from the inner face of said die.
16. In combination, an annular crushing die revolving in an approximately vertical plane and having an internal crushing face, 60 a movable and rotatable crushing roll within and eccentric of said die and having a peripheral crushing face reciprocal to the inner face of said die, means for revolving one of said parts, non-rotative movable means on which said roll is rotatably mounted, oppositely obliquely outwardly inclined holding means inwardly of the axis of said roll and opposite and adapted to act obliquely radially outwardly toward said non-rotative means to hold said roll outwardly toward the inner face of said die to resist a crushing pressure therefrom, and thrust means intermediate of said holding means and transmitting the stress of one to another.

In witness whereof, I have hereunto signed my name in the presence of two subscribing witnesses.
